UNITED STATES PATENT OFFICE

124,326

DESIGN FOR A TIRE GROOVER

William Mossback and Joseph A. Menard, Seattle, Wash., assignors to Timesaver Products Company, Seattle, Wash., a corporation of Washington

Application May 27, 1940, Serial No. 92,631

Term of patent 14 years

To all whom it may concern:

Be it known that we, William Mossback and Joseph A. Menard, citizens of the United States of America, residing at Seattle, in the county of King and State of Washington, have invented a new, original, and ornamental Design for Tire Groovers, of which the following is a specification, reference being had to the accompanying drawing, forming part thereof.

Figure 1 is a top perspective view of a tire groover, showing our new design;

Figure 2 is a side elevational view thereof; and Figure 3 is a top plan view thereof.

We claim:

The ornamental design for a tire groover, as shown.

WILLIAM MOSSBACK.

JOSEPH A. MENARD.
